UNITED STATES PATENT OFFICE

THOMAS J. MADIGAN, OF NEW YORK, N. Y.

CONTINUOUS ROTARY BEATER

Application filed October 23, 1929. Serial No. 401,841.

The invention relates to a continuous rotary beater.

The object of the present invention is to improve the construction of rotary beaters for beating eggs, whipping cream, and similar operations, and to provide a simple, practical and efficient rotary beater of strong, durable and comparatively inexpensive construction, adapted to be operated by a vertically reciprocating motion of one hand and capable of imparting a continuous rotary movement in the same direction to a plurality of agitator members and at the same time enable the beater to be maintained by the pressure of the hand in a vertical or inclined position so as to effectively operate on all portions of the contents of a vessel and in different parts of the same without liability of the device accidentally slipping, and at the same time leaving the other hand of the operator free to supply the proper ingredients to the vessel.

With these and other objects in view, the invention consists in the construction and novel combination and arrangement of parts hereinafter described, illustrated in the accompanying drawings, and set forth in the claims hereto appended, it being understood that various changes in the form, proportion, and minor details of construction, within the scope of the claims, may be resorted to without departing from the spirit of the invention or sacrificing any of the advantages thereof.

In the drawings:

Figure 1 is a side elevation of a rotary beater constructed in accordance with this invention.

Fig. 2 is an enlarged detail sectional view illustrating the construction of the gearing for converting the vertically reciprocating motion into a continuous rotary motion in the same direction.

Fig. 3 is an enlarged detail view, partly in section, of the bracket and the gearing.

Fig. 4 is a detail sectional view illustrating the means for guiding the rack bar in its vertical reciprocation.

Fig. 5 is a detail view illustrating the manner of mounting the rotary agitator members.

In the accompanying drawings, in which is

illustrated the preferred embodiment of the invention, 1 designates a bearing bracket designed to be constructed of sheet metal or other suitable material and provided at opposite sides of its lower portion with tubular beads or sleeves 2 for the reception of the upper ends of the sides of an approximately U-shaped frame 3 constructed of stout wire or other suitable material and constituting a support for a pair of rotary agitator members. The approximately U-shaped frame is composed of similar spaced sides and a connecting portion 4, the sides being bowed or curved outwardly at their lower portions at 5 to provide an approximately circular formation. The connecting portion 4, which is arranged at the lower end of the frame 3, is straight, and is provided with a central depending sharp pointed spur 6 adapted to rest upon the bottom of a vessel for supporting and fulcrumming the beater to enable the same to be maintained either in a vertical position or in an inclined position. The supporting spur 6, which fulcrums the device on the bottom of the vessel, enables the operator to tilt the beater in any direction from a vertical position by simply moving laterally the hand which is used for operating the beater. This will permit the beater to operate on all portions of the contents of the vessel and to operate in different parts thereof so as to thoroughly beat the contents. The upper ends of the straight portions of the sides of the frame 3 may be secured within the hollow beads 2 in any desired manner, but instead of connecting the sides of the frame to the bracket as shown and described, the frame and the bracket may be constructed in any other suitable manner for effecting connection of such parts.

The sides of the frame 3 have mounted on them the rotary agitator members 7, constructed of metal or other suitable material, and consisting of a substantially circular lower portion 8 and spaced upper side portions 9 which are secured at their upper ends to pinions 10 mounted on the sides of the frame contiguous to the bearing bracket and immediately below the same. The circular portions 8 of the rotary agitators are provided with

perforations 11 to receive the sides of the frame 3, and they are mounted on the same at the ends of the connecting portion 4. This provides a lower bearing for the rotary agitator members, the pinions 10 forming upper bearings for the agitator members. By this construction, the rotary agitator members are journaled on the sides of the frame 3 at the top and bottom thereof, and they are arranged to clear each other during their rotation and are maintained in proper relative position by the meshing of the pinions 10.

The pinions 10 are arranged in horizontal position when the beater is vertical, and one of the pinions meshes with a vertical gear wheel 12, which is mounted on a main horizontal shaft 13 journaled in spaced bearings 14 of the frame. The bearings 14 are preferably formed by aligned ears which are located at opposite sides of the central portion of the bearing bracket. The bearing bracket is provided with a central opening 15' in which operates a lower gear 16 mounted on the shaft 13 and meshing with an upper gear 23 or pinion 17 provided with a shaft or spindle 18 which is mounted in vertically elongated bearing openings 19 of upper spaced bearings 20. The upper spaced bearings are preferably formed integral with the bearing bracket and are located at opposite sides of the pinion or gear 17, which meshes with a vertically movable rack bar 21 operating in an upper guide 22 of the bearing bracket and provided with a longitudinal slot 23 through which passes a guide pin 24. The guide pin 24 is mounted in the spaced bearings 20 of the bearing bracket and is also adapted to serve as a convenient fastening device for connecting the terminals of the bearings 20 to prevent spreading of the same. The guide 22 consists of a horizontal arm of the bracket and is composed of spaced sides and connecting portions which form an outer guide opening for the rack bar, as clearly illustrated in Fig. 4 of the drawings.

The rack bar is provided with an extended lower end 25 to which is suitably connected the lower end of a coiled spring 26 which is connected at its upper end at 27 to the guide 22. The device is adapted to be positively operated by a downward movement of one hand of the operator, which carried the rack bar downwardly through the guide 22, thereby rotating the pinion or gear 17 and maintaining during such movement the pinion or gear 17 in mesh with the lower pinion or gear 15', and thereby imparting rotary movement to the shaft 13 and rotary movement to the agitator members 7 through the gearing connecting the said agitator members with the shaft 13. This downward movement of the rack bar also distends and places under tension the coiled spring 26 and the latter operates to move the rack bar vertically as

the operator relieves the device of pressure. When the rack bar moves upwardly the shaft 18 of the upper pinion or gear 17 is carried to the upper ends of the elongated bearing openings 19 and the said upper pinion or gear 17 is lifted out of mesh with the lower pinion or gear 15' so that there is no positive actuation of the agitator members during such upward movement of the rack bar. This will enable an exceedingly light spring 26 to be employed for effecting this upward movement of the rack bar, which is instantly returned to its raised position to enable the operator to again actuate the beater by downward pressure of the hand. An easy, effective operation of the beater is thereby secured, and at the same time a rapid continuous forward rotation of the agitator members is obtained, as the momentum of the agitator members will cause the same to continue their forward rotation during the upward movement of the rack bar. By this means an easy, rapid operation of the beater is obtained, and as the rotary agitator members are not reversed at the end of each stroke, much greater speed and power is obtained than is the case when the direction of rotation of the agitator members is reversed at the end of each stroke.

The rack bar is provided at its upper end with a suitable handle 28 which may be of any desired formation. The coil spring 26, which lifts the rack bar, may be connected with the same and with the bearing bracket in any desired manner.

What is claimed is:

1. A beater of the class described, including a rotary agitator member and gearing for imparting a continuous forward rotary movement to the agitator member, including upper and lower intermeshing gears, one of the gears being shiftable into and out of mesh with the other gear, and a reciprocating rack bar meshing with the shiftable gear and arranged to hold the said gears in mesh for actuating the agitator member during one movement of the rack bar and capable of moving the shiftable gear out of mesh during the movement of the rack bar in the opposite direction.

2. A beater of the class described, including a rotary agitator member and gearing for imparting a continuous forward rotary movement to the agitator member, including upper and lower intermeshing gears, one of the gears being shiftable into and out of mesh with the other gear, a reciprocating rack bar meshing with the shiftable gear and arranged to hold the said gears in mesh for actuating the agitator member during one movement of the rack bar and capable of moving the shiftable gear out of mesh during the movement of the rack bar in the opposite direction, said rack bar being adapted to be operated by pressure of the hand in

its agitator actuating movement, and a spring connected with the rack bar for automatically moving the same in the opposite direction.

5 3. A beater of the class described, comprising a bearing bracket, a plurality of rotary beater members carried by the bearing bracket, gearing for connecting the rotary beater members and for imparting a continuous forward rotary movement to the same, said gearing including a pair of upper and lower gears, one of the gears being shiftable to move into and out of mesh with the other gear, a vertically reciprocating rack bar meshing with 10 the shiftable gear and adapted when moved downwardly to hold the shiftable gear in mesh and operate the beater members, and a spring connected with the rack bar and with the bracket for moving the rack bar upwardly, the upward movement of the rack bar operating to carry the shiftable gear out of mesh.

4. An agitator of the class described, including a bearing bracket, rotary agitator members carried by the bearing bracket, gearing for imparting a continuous forward rotary movement to the agitator members including upper and lower gears, the upper gear being shiftable to move into and out of mesh with the lower gear, a vertically reciprocating rack bar meshing with the upper gear and adapted in its downward movement to hold the shiftable gear in mesh for actuating the agitator members, said rack bar 30 being provided with a longitudinal slot, a guide pin mounted on the bearing bracket and passing through the slot of the rack bar and arranged adjacent the shiftable gear for maintaining the rack bar in mesh with the same, and a spring connected with the bearing bracket and with the rack bar for moving the rack bar upwardly, the upward movement of the rack bar carrying the shiftable gear out of mesh.

45 5. An agitator of the class described, including a bearing bracket, rotary agitator members carried by the bearing bracket, gearing for imparting a continuous forward rotary movement to the agitator members including upper and lower gears, the upper gear being shiftable to move into and out of mesh with the lower gear, a vertically reciprocating rack bar meshing with the upper gear and adapted in its downward movement to hold the shiftable gear in mesh for actuating the agitator members, said rack bar being provided with a longitudinal slot, a guide pin mounted on the bearing bracket and passing through the slot of the rack bar 50 and arranged adjacent the shiftable gear for maintaining the rack bar in mesh with the same, a horizontal guide carried by the bracket and receiving the rack bar, and a spring connected with the horizontal guide and with the rack bar for moving the lat-

ter upwardly, the upward movement of the rack bar operating to carry the shiftable gear out of mesh.

6. A beater of the class described, including a bearing bracket having elongated bearing openings, rotary agitator members carried by the bracket, gearing for imparting a continuous forward rotary movement to the agitator members including a pair of gears, one of the gears having a shaft arranged in 70 the elongated bearing openings and movable therein to carry the shiftable gear into and out of mesh with the other gear, a reciprocating rack bar actuating the shiftable gear and adapted to be positively actuated in one 75 direction, and a spring for moving the rack bar in the opposite direction.

In testimony whereof I have hereunto set my hand.
